(57) **CLAIM**

The ornamental design for an apparatus for retaining bags, as shown and described.

DESCRIPTION

FIG. 1 is a perspective view of an apparatus for retaining bags in accordance with the invention disclosed and claimed herein;

FIG. 2 is a front view of the apparatus for retaining bags of FIG. 1;

FIG. 3 is a left side view of the apparatus for retaining bags of FIG. 1 (the right side view being a mirror image of the left side view);

FIG. 4 is a bottom view of the apparatus for retaining bags of FIG. 1;

FIG. 5 is a rear view of the apparatus for retaining bags of FIG. 1;

FIG. 6 is a perspective view of an alternative embodiment of the apparatus for retaining bags in accordance with the invention disclosed and claimed herein;

FIG. 7 is a front view of the apparatus for retaining bags of FIG. 6;

FIG. 8 is a left side view of the apparatus for retaining bags of FIG. 6 (the right side view being a mirror image of the left side view);

FIG. 9 is a bottom view of the apparatus for retaining bags of FIG. 6;

FIG. 10 is a rear view of the apparatus for retaining bags of FIG. 6;

FIG. 11 is a perspective view of a second alternative embodiment of the apparatus for retaining bags in accordance with the invention disclosed and claimed herein;

FIG. 12 is a front view of the apparatus for retaining bags of FIG. 11;

FIG. 13 is a left side view of the apparatus for retaining bags of FIG. 11 (the right side view being a mirror image of the left side view);

FIG. 14 is a bottom view of the apparatus for retaining bags of FIG. 11; and,

FIG. 15 is a rear view of the apparatus for retaining bags of FIG. 11.

It will be understood that the hidden lines shown throughout the drawings are for illustration only, forming no part of the claimed design.
